UNITED STATES PATENT OFFICE.

JOHN MORAN MURPHY, OF KINGSTOWN, IRELAND.

MECHANICAL TOY.

1,323,900.

Specification of Letters Patent.

Patented Dec. 2, 1919.

Application filed May 26, 1919. Serial No. 299,724.

To all whom it may concern:

Be it known that I, JOHN MORAN MURPHY, a subject of the King of Great Britain, residing in Kingstown, Ireland, have 5 invented a certain new and useful Improved Mechanical Toy, of which the following is a specification.

The invention consists in a mounting for model ships, tanks or the like by which 10 they may be manipulated so as to travel over a suitable surface at varying speeds and in any required direction.

The models mounted in this manner lend themselves to a naval game in which 15 vays may be attacked, battle ships may endeavor to elude submarines, or two vessels may race to a given point.

The models are supported by a pair of wheels, running freely on axles at the same 20 transverse section, and by a member provided with two claws placed in the fore and aft line of the model and either in front of or behind the wheels. The member carrying the claws is connected with a vertical spindle to the upper end of which is 25 secured a horizontal grooved pulley wheel. A thread is passed around the pulley, the two ends of the thread, which may be of any required length, being held in the 30 hands of the operator. When the model is placed on a surface covered with a suitable material such as cloth, baize, or a stretched sheet and the pulley is turned so that the points of the claws are pointing backward, 35 any oscillation imparted to the pulley by pulling either end of the thread will cause one claw to be withdrawn and the model take a step forward about the other claw as a pivot. If the pulley is rotated in opposite 40 directions alternately through equal arcs, the model will progress forward in a constant direction. Successive movements of the pulley in the same direction will alter the course, so that the model can, consequently, be steered to follow any required 45 path.

In the accompanying drawings, which 50 represent examples of model ships according to the invention, Figure 1 is a side elevation of a ship; Fig. 2 is a rear view; Fig. 3 shows in side elevation a ship with slightly modified means for propulsion and Figs. 4 and 5 show details of the propelling device.

Referring to Figs. 1 and 2, A is the model 55 ship, B', B² are wheels mounted on trans-

verse axles b', b². C is a member provided with claws c', c² shown on a larger scale in Figs. 4 and 5 and placed in the fore and aft line of the model. A grooved horizontal pulley D carries a vertical spindle d to the lower horizontal extension e of which the member C is pivoted. This arrangement enables the claws c', c² to pass easily over an uneven surface. The points of the claws are bent backward and are adapted to engage with a suitable surface, so that oscillations imparted to the pulley wheel D cause, as explained above, the model to progress in any required direction. A thread F is passed preferably about twice around the 60 grooved pulley D; this thread is guided in a wire guide G supported by a loose sleeve g surrounding the spindle d and placed between the pulley D and the deck of the vessel. The member C can be inclined at 65 any angle to the fore and aft line and the course altered accordingly. The thread is of sufficient length to enable the operator to be at any convenient distance from the 70 model.

Models may be driven tandem by the same thread passing around each pulley, if the pulleys have the same diameters and there is the same ratio between the diameters of the pulleys and the distance apart of the 75 claws.

The models are loaded with weights disposed between the wheels and the clawed member.

In the modification shown in Fig. 3 the 80 pulley D' is smaller and is connected with the member C by gearing H, H'.

Having thus described the nature of the said invention and the best means I know of carrying the same into practical effect, I 85 claim:—

1. A mounting for model ships, tanks and the like, comprising a pair of wheels on the same transverse section of the model and a member on the fore and aft line provided 90 with claws, adapted to engage with the material on which the model is placed, a vertical spindle secured to the model, a pulley on the spindle, manually operated means for imparting oscillations to the pulley and means connecting the spindle to said member.

2. A mounting for model ships, tanks and the like, comprising a pair of wheels on the same transverse section of the model and a 105

110

- member on the fore and aft line provided with claws, adapted to engage with the material on which the model is placed, a vertical spindle, a grooved pulley associated with said spindle, a thread in the groove of said pulley adapted to be manually manipulated to impart oscillations to the spindle and means connecting the spindle to said member.
- 10 3. A mounting for model ships, tanks and the like, comprising a pair of wheels on the same transverse section of the model and a member on the fore and aft line provided with claws, adapted to engage with the material on which the model is placed, a vertical spindle, a grooved pulley associated with said spindle, a thread in the groove of said pulley adapted to be manually manipu-
- 15

lated to impart oscillations to the spindle, a sleeve on said spindle and a guide for 20 said thread loosely supported by said sleeve.

4. A mounting for model ships, tanks and the like, comprising a pair of wheels on the same transverse section of the model and a member on the fore and aft line provided 25 with claws, adapted to engage with the material on which the model is placed, a vertical spindle secured to the model, a pulley on the spindle, manually operated means for imparting oscillations to the pulley 30 and toothed gearing connecting the spindle to said member.

In testimony whereof I have signed my name to this specification.

JOHN MORAN MURPHY.
